IMPROVEMENT IN REVOLVING FLUE-CLEANER.

G. E. BINGHAM, OF MILWAUKEE, WISCONSIN.

Letters Patent No. 60,128, dated December 4, 1866.

SPECIFICATION.

TO ALL WHOM IT MAY CONCERN:

Be it known that I, G. E. BINGHAM, of Milwaukee, in the county of Milwaukee, and State of Wisconsin have invented a new and useful Improvement in Revolving Flue-Cleaner; and I do hereby declare that the following is a full, clear, and exact description thereof, which will enable others skilled in the art to make and use the same, reference being had to the accompanying drawings forming part of this specification, in which—

Figure 1 is a perspective view of my improved flue-cleaner.

Figure 2 is a side view of the same, the detachable bars being removed.

Figure 3 is an end view of the same.

Figure 4 is a vertical cross-section of the same, taken through the line $z z$, fig. 2.

Figure 5 is a detailed sectional view of the same, taken through the line $y y$, fig. 3.

Similar letters of reference indicate like parts.

My invention has for its object to furnish an improved machine for cleaning lime scale, &c., from boiler flues; and it consists in the revolving flue-cleaner, formed by combining the wooden bars, metallic heads, binding bands, binding rods, and shaft with each other, as hereinafter more fully described.

J are the standards, upon the upper ends of which are formed the bearings for the journals of the shaft I, as shown in figs. 2 and 3. E are metallic heads securely attached to the shaft I, so as to revolve with it. The heads E are made with inwardly projecting flanges D for the ends of the bars F and A to rest upon, as shown in figs. 2 and 5. F are wooden bars, the ends of which rest upon the flanges D, formed upon the inner side of the heads E, and they are secured in place by the binding bands C and B. The bars A are made a little shorter than the bars F, so that they may be removed and inserted without removing the bands C. To enable this to be done, the portion b' , of the bands B, that cover the bars, is hinged to the main parts of said bands, as shown in figs. 1, 2, and 4. The ends of the bands B and C are secured to each other by being bent outward, and having a bolt passed through them, as shown in the drawings. G are the binding rods which pass through ears formed upon the edges of the heads E, and they are held in place and tightened by nuts screwed upon their ends upon each side of the said ears, as shown in the drawings. I is an open spring ring, placed within the cylinder to support the middle parts of the bars F and A, as shown in figs. 2 and 5. H is a loose pulley, and K is a driving pulley, which are attached to one of the ends of the shaft I in the ordinary manner. In using the apparatus, the hinged parts b' of the bands B are turned back, and the bars A removed. The flues to be cleaned are then placed in the interior of the machine, together with a quantity of iron turnings, or other suitable hard substance. The flues and iron turnings are then wet with water, and the machine closed and set in motion. The lime or other incrustation, as it is ground from the flues, escapes from the machine through the spaces between the bars F and A. The machine must be stopped, and the progress of the work examined every few hours, so that the flues and iron turnings may be kept wet or moist. In this way, with a cylinder two feet in diameter, from twenty to thirty flues can be cleaned at a time, and even a greater number, when the cylinder is made larger, thereby greatly diminishing the time and expense of cleaning a set of boiler flues.

What I claim as new, and desire to secure by Letters Patent, is—

The revolving flue-cleaner, formed by the combination and arrangement of the heads E, wooden bars F and A, binding bands B and C, binding rods G, and shaft I, substantially as herein described, and for the purposes set forth.

G. E. BINGHAM.
